COMBINED SINK SUPPORT AND CLAMP-DOWN TOOL

Thomas Albanese, 116 Norlen St., Las Vegas, Nev.

Filed Nov. 4, 1963, Ser. No. 77,286

Term of patent 3½ years

(Cl. D54—13)

Fig. 1

Fig. 2

FIGURE 1 is a view in perspective as viewed from the front of a combined sink support and clamp-down tool embodying my new design; and

FIGURE 2 is a front elevational view in collapsed form. The broken line disclosure in FIGURE 1 is for illustrative purposes only.

I claim:

The ornamental design for a combined sink support and clamp-down tool, substantially as shown and described.
